IMPROVED BLACKING BRUSH.

CHARLES MULCHAHEY, OF SPRINGFIELD, MASSACHUSETTS.

Letters Patent No. 60,226, dated December 4, 1866; antedated November 25, 1866.

SPECIFICATION.

TO ALL WHOM IT MAY CONCERN:

Be it known that I, CHARLES MULCHAHEY, of Springfield, Hampden county, Commonwealth of Massachusetts, have invented a new and improved Boot-Blacking Brush; and I do hereby declare that the following is a full and exact description thereof, reference being had to the accompanying drawings, and to letters of reference marked thereon.

This invention consists in arranging on the upper side of an ordinary polishing brush a box of blacking, and attaching to the cover of the same the smaller brush used to spread the paste. In the drawings—

Figure 1 is a perspective view of my invention.

Figure 2 is a cross-section of the same.

Figure 3 is a plan view of the cover of the box and small brush.

Figure 4 is a plan view of the brush with the cover of the box removed.

In construction I usually attach to the top of the polishing brush, A, the rim, B, inside of which I place the box of blacking, C, secured in place by the set-screw *a* and points *b b*; over this I place the cover D, having on its top the small spreading brush *e*, provided with a handle *d*; this cover fits over the rim B, thus preventing the drying of the blacking when closed and furnishing a convenient brush for spreading the paste when removed from the box.

In using this arrangement, I remove the smaller brush and spread on the paste with it, and in doing this and in taking it from the box I have a convenient handle, E, and the box being fastened to the other brush, also having a handle, the fingers are not soiled by being brought in contact with the blacking, as is the case ordinarily. I do not wish to confine myself to the exact arrangement herein described, as I may attach the box in a different manner, and the small brush may even be used separate from the larger and not attached to the top of the box, or the cover of the box may be attached to the polishing brush and the box itself set in it, as desired.

Now, having described my invention, what I claim as new, and desire to secure by Letters Patent, is—

1. Attaching to the top of an ordinary polishing brush for boots, shoes, &c., a blacking box fitted in a case B, formed to receive it.

2. Attaching to this box, or to the case which is formed to receive it, the smaller spreading brush *e*, by means of a rim or cover, arranged as shown and described.

CHAS. MULCHAHEY.
